UNITED STATES PATENT OFFICE.

HOWARD G. MACDONALD, OF PITTSBURGH, PENNSYLVANIA, ASSIGNOR, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

CIRCUIT-BREAKER.

1,087,500.

Specification of Letters Patent. Patented Feb. 17, 1914.

Application filed June 8, 1908. Serial No. 437,345.

To all whom it may concern:

Be it known that I, HOWARD G. MACDONALD, a citizen of the United States, and a resident of Pittsburgh, in the county of Allegheny and State of Pennsylvania, have invented a new and useful Improvement in Circuit-Breakers, of which the following is a specification.

My invention relates to automatic circuit interrupters, and it has for its object to provide an oil-immersed circuit-breaker of this class that shall be simple and durable in construction and so arranged as to preclude the possibility of maintaining the contact members in closed position under conditions which would normally render the automatic release member active.

The operating mechanism of my circuit-breaker comprises, in general, a toggle joint formed by suitable levers and links by which the movable contact members may be brought into engagement with the stationary members but which may be released in either direction.

Figure 1 of the accompanying drawings is an elevation of a circuit interrupter constructed in accordance with my invention, the inclosing casing being in section to disclose the operating mechanism. Fig. 2 is a plan view of the mechanism shown in Fig. 1; Figs. 3 and 4 are views showing the relation of parts of the operating mechanism when the interrupter occupies the one or the other of its open-circuit positions, and Fig. 5 is a detail view of the release mechanism. Figs. 6 and 7 are, respectively, an elevation and a plan view of a structurally modified operating mechanism which may be substituted for that shown in the other figures.

Referring to Figs. 1 to 5, inclusive, of the drawings, the device here illustrated comprises a plurality of stationary contact members 1, movable contact members 2 to cooperate therewith, a handle lever 3, an operating mechanism for the movable contact members, a release mechanism and electro-responsive actuating means therefor. The parts of the interrupter are all supported by an intermediate portion 4 of the casing which comprises, in addition to this part, a cover 5 and an oil-containing tank 6. The stationary contact members 1 are secured to an insulating plate 7 which lies in a hori-

zontal plane and is secured to projections 8 on the body of the casing. The movable contact members 2 are resiliently secured to an insulating bar 9 and are connected to stationary terminals 10 on the insulating plate 7 by means of flexible conducting shunts 11. The insulating bar 9 is suspended from one end of a bell crank lever 12 by links 14, the said lever being rotatably mounted on a stationary shaft 13. The other end of the bell crank lever 12 is connected to a relatively stationary shaft 15 by means of a pair of links 16 and 17 which form a toggle joint. An actuating block 18 is operatively connected to the handle lever 3 and is adapted to close the circuit interrupter by forcing the links into a substantially straight line. The release mechanism comprises a bell crank lever 19 having rollers 20 and 21 mounted on the respective ends of its arms, and lever arms 22 and 23 which are keyed to a shaft 24 on which the bell crank lever 19 is fulcrumed, the arm 22 being provided with a projection 25 against which one arm of the bell crank lever 19 is held, under normal conditions, by means of a spring 26. A well known form of electro-responsive means by which the release mechanism is operated, two of these magnets being employed in the device illustrated. Each magnet comprises a movable core member 28 to which a striker or hammer rod 29 is secured, adjustable means for varying the air-gap between the stationary and movable core members, and a coil for energizing these members.

The operation of the device is as follows: Assuming that the interrupter is closed and that the parts of the operating mechanism occupy the positions shown in Fig. 1; the circuit may be automatically interrupted by energizing the electro-magnets. When energized, the movable core members of these magnets are attracted toward the stationary core members and the hammer rods strike the arms 22 and 23 and move them, together with the bell crank lever 19, in a clockwise direction, in opposition to the spring 26 until the roller 20 reaches a position which will permit the toggle links 16 and 17 to operate under the action of the weight imposed by the parts 14, 9 and 2 and move the parts 3, 18 and 19 to the positions shown in Fig. 3. The interrupter is closed, when the parts

are as indicated in Fig. 3, by depressing the handle lever 3, since the projection 31 of the block 18 engages a pin 32 which connects the links 16 and 17 together and projects laterally therefrom. If the electro-magnet is sufficiently energized when the contact members are brought together in again closing the breaker, the shoulder 30 of the block 18 will not engage the roller 21 when the handle lever 3 is moved downwardly from the position shown in Fig. 3, and, consequently, the toggle links will continue their movement to substantially the positions shown in Fig. 4 and the contact members will therefore remain in engagement for only a short period of time. It is possible to close the interrupter when the parts are arranged as shown in Fig. 4 by moving the handle lever 3 upwardly, since a shoulder 33 of the block 18 will engage the pin 32 and move the links 16 and 17 to substantially the positions indicated in Fig. 1. Again assuming that the circuit interrupter is closed, the parts being arranged as shown in Fig. 1; if it is desired to manually open the interrupter, the handle lever 3 may be raised, thereby causing a rotative movement of the bell crank lever 19 by reason of the engagement of a projection 31 of the block 18 with the roller 21 and a consequent removal of the roller 20 from its locking engagement with the link 17.

Referring to Figs. 6 and 7, in which like parts are designated by the same reference characters, a latch 34 having a notch 35 near its end is substituted for the bell crank lever 19 and the block 18 is replaced by a lever 36, an arm 37 of which is provided with a roller to engage the notch 35. The latch 34 is resiliently held against the projection 25 of the arm 22 and will be moved out of its engagement with the roller of the arm 37 by the hammer rod 29 when the electro-magnet is energized.

It will be understood that various structural modifications may be effected within the scope of my invention, and, consequently, I desire that only such limitations shall be imposed as are specified in the appended claims.

I claim as my invention:

1. In a circuit-breaker, the combination with stationary and movable contact members, an operating lever, a handle lever, a shaft to which the handle lever is secured and toggle links interposed between said operating lever and said shaft, of means operated by said handle lever to operatively engage either side of the pivot pin which connects said toggle links together to close the breaker.

2. In a circuit interrupter, the combination with stationary and movable contact members, an operating lever and a handle lever, of an operative connection between the

handle lever and the operating lever comprising toggle links and an operating block having lost-motion with reference to said links and having projections to respectively engage the toggle joint at opposite sides. 70

3. In a circuit interrupter, the combination with stationary contact members, a movable contact member, an operating bell crank lever from which the movable member is suspended, a rotatable shaft, a handle lever secured to said shaft, an operating block and a pair of toggle links interposed between the bell crank lever and the shaft, said operating block being fixed to the shaft and having projections to engage the link joint at either side and having lost-motion with reference thereto. 75

4. In a circuit-breaker, the combination with stationary and movable contact members and means for holding the members in engagement, of an operating mechanism comprising toggle links, manually operated means for moving said links in either direction into approximate alignment to effect engagement of said contact members and for releasing said links, and electro-magnetic means for releasing said links. 80

5. In a circuit interrupter, the combination with stationary and movable contact members, an operating bell crank lever, a handle lever having an operating block and a pair of toggle links interposed between the bell crank lever and the handle lever and adapted to be operated in either direction by said operating block, of a movable stop for engaging one of the toggle links to hold the contact members in engagement, and electro-responsive means for automatically displacing the stop under predetermined conditions. 95

6. In a circuit interrupter, the combination with stationary and movable contact members, two substantially parallel shafts, an operating bell crank lever and a handle lever mounted upon the respective shafts, a pair of toggle links interposed between the operating lever and the handle lever, an operating block rigidly mounted on the handle lever shaft and having projections to engage the respective sides of the pivot which connects the toggle links together, of means for so acting upon one of the links as to hold the contact members in engagement and electro-responsive means for preventing a continued engagement of the contact members under predetermined conditions. 105

7. In a circuit interrupter, the combination with stationary and movable contact members, of an operating mechanism comprising toggle links which may be moved in either direction from a position of approximate 110 alignment to separate the contact members, a stop for normally preventing movement of the toggle links in one direction to separate the contact members, and a handle lever having means for engaging said links to move 115 120 125 130

them into locking position from either side of their position of alinement.

8. In a circuit interrupter, the combination with stationary and movable contact members, of an operating mechanism comprising toggle links which may be moved in either direction from approximate alinement to separate the contact members, a stop serving to hold the toggle links in unstable equilibrium for preventing movement thereof in one direction to separate the contact members, means dependent upon predetermined conditions for withdrawing the stop, and a handle lever having means for moving the stop from its holding position.

9. In a circuit interrupter, the combination with stationary and movable contact members, two substantially parallel shafts, an operating lever and a handle lever mounted

upon the respective shafts, two pivotally connected toggle links interposed between the handle lever and the operating lever, and means projecting from the handle lever to engage either side of the pivot pin which connects said toggle links, of a movable stop for engaging one of said toggle links to prevent the separation of the contact members, and an electro-responsive release mechanism for displacing the stop under predetermined conditions.

In testimony whereof, I have hereunto subscribed my name this 29th day of May, 1908.

HOWARD G. MACDONALD.
